ABSTRACT OF THE DISCLOSURE

A switching device for switching conductors of a printed circuit board comprises a generally V-shaped contact spring one arm of which is fixedly connected to one conductor of the board and the other arm of which can be moved into and out of engagement with another conductor of the board and is snapped into engagement by the pressure of an actuating member against a spiral coil provided intermediate the length of said other arm when the actuating member is moved past a predetermined position with reference to the coil.

The present invention relates to a switching device, especially suitable for application to printed circuit boards. Such switching devices comprising push button operating means are used for instance in pushbutton sets for pulsing in telephone instruments. These pushbutton sets which must be mounted in the space provided for the conventional dial, must not be bulky, whereby the design of the device presents a problem, especially as the space available for the required contact springs is limited.

A known design uses reed contacts that are located substantially in parallel relationship to the circuit board and conveniently secured to the same. When actuated, the movable springs make or break the contact with fixed contacts provided on the board. In this arrangement, however, it becomes necessary to use short contact springs, which has inherent disadvantages, such as a bad contact sliding at the closure moment of contact engagement, which may jeopardize an effective operation, as well as cause a relatively high deflection stress on a short spring length.

In another known construction, reed springs of U-form are mounted on a support projecting from the board, so that the arms of the U-formed springs are placed perpendicularly to the board. By this arrangement an increased spring length is obtained in comparison with the first-mentioned arrangement. The ends of the spring arms are inserted into holes in the board to cooperate with fixed contacts arranged on the edges of the holes. The spring movement is obtained by displacement of the push button in a direction tangential to the spring. In order to obtain the required magnitude of the movement of the contact it is necessary to provide the spring with a deflection that is laterally displaced when pressing the button. This device, however, has the disadvantage that the deflection of the contact spring might cause fracture of the spring.

The device of the invention is similar to this last-mentioned construction in that the springs are located on supports projecting from the board and have contact arms that are substantially perpendicular to the board. It constitutes, however, an improvement of the known device in that the deflection length of the spring is considerably greater although the spring still occupies a reduced space. The spring furthermore is not subjected to bends that are likely to cause a fracture. These advantages are obtained by the contact springs being made of resilient

2

wire and the spring arm carrying the movable contact at an intermediate portion having a coil spiral of cylindrical form, the center axis of which is parallel to the plane of the board.

These and other advantages of the invention will be understood from the following description that is made with reference to the attached drawing.

In the drawing FIGURE 1 shows an exploded view of the pushbutton mechanism and FIGURE 2 shows the position of the contact spring in three different phases of the pushbutton movement.

The pushbutton mechanism is supported by a base plate 1 of insulating material that may be common to a plurality of pushbuttons. The base plate has secured thereon an elastic support 2 for each pushbutton mechanism. A pushbutton 3 has a center shaft 4 that fits into a hole 5 in the base plate 1, which hole serves as a guide for the shaft. As an additional guiding means for the pushbutton 3 a cover plate 6 with a square hole 7 is provided, through which hole the upper square portion of the pushbutton may protrude. To mount the mechanism, the shaft 4 is inserted into the hole 5, whereafter the cover plate 6 is placed over the upper part of the pushbutton and in a convenient manner secured to the base plate 1 at a predetermined distance from the same. For holding the button in an inactive position the button is provided with a helical spring 10, located on an upper part 8 of the center shaft, which spring normally pushes the button 3 upwards, so that its flange 9 rests against the bottom side of the cover plate 6.

On the bottom side of the base plate a circuit board 11 with printed circuits (not shown in the figure) is provided. The switching device further comprises two movable contact springs 13 and 14, one being a mirror image of the other. The contact springs are made of resilient wire and designed to be mounted on the support 2. For this purpose they are provided with a coil spiral 19 at their upper part, which coil spiral fits into a recess 21 in the support 2, where it is retained without being squeezed. The recess 21 has an upper opening that is somewhat narrower than the outer diameter of the coil spiral. The coil spiral may, however, be pushed down through this opening because the support 2 is made of an elastic material.

Each spring has at the end of one arm a cylindrical contact 17 for cooperation with a fixed contact 12. At an intermediate portion of this arm is provided with a coil spiral 20 which partly serves to absorb the deflection stresses during the actuation of the spring and partly serves as an actuation surface for the pushbutton, thereby providing a convenient trigger point as is explained below. The other arm of the spring is straight and, when mounting the spring in the support 2, this arm is inserted into a hole 25 through the base plate 1 and the printed circuit board 11, so that this arm may be soldered to a printed circuit on the bottom side of the circuit board as shown at 15 and 16 (FIG. 2). The cylindrical contact 17 provided on the end of the other arm is inserted into another hole 26. The fixed contact 12, made in form of a wire, is located in a groove 27 in the bottom side of the base plate and has a V-formed portion 18 for cooperation with the contact 17. The wire 12 may at a convenient place cross the circuit board and be connected to a conductor on this board.

The pushbutton is provided with an actuation member 23 for actuating the springs. The actuation member is at its lower end provided with two symmetrical curved recesses 24 for actuating the coil spirals 20 of the springs 13 and 14. At the first moment of actuation the vertical diameter of the coil spirals are practically in the same plane as the vertical side of the respective actuation member, a fact that produces the desired trigger point effect

(see FIG. 2). A person pressing the pushbutton has, in order to overcome the reaction of the spring, to increase the force so that the springs are displaced laterally thereby making contact with the fixed contacts. At the moment this occurs he cannot avoid pressing down the button to its lowermost position, whereby the actuation member slides down between the coil spirals 20 of the contact springs, the coil spirals resting against the side surfaces 28. By this trigger point effect a minimum length of the spring movement is obtained.

I claim:

1. A switching device for switching conductors of a printed circuit board, said switching device comprising in combination:

a printed circuit board mounting a support protruding from one side of the board; 15

a substantially V-shaped contact spring supported on said support straddling the same, one of the arms of the spring being connected to one of the conductors of the board and the other arm being switchable into and out of contact with another conductor and biased into one of its switching positions, said other arm having intermediate its length a spiral coil the center axis of which is substantially parallel to the plane of the board; and 20

an actuating member supported by said board on the side thereof mounting the support and displaceable normal to the plane of the board, said member having on one end a portion engaging said spiral coil upon depressing the actuating member from an inactive position into a predetermined depressed position with reference to the plane of the board, engagement of said portion with said spiral coil displacing the latter substantially parallel to the plane of the board thereby flexing said other spring arm into the other one of its switching positions and retaining said other arm in said other switching position. 30

2. The switching device according to claim 1 wherein said portion of the actuating member terminates in a curved taper, the curvature of said taper mating with the outside of said spiral coil in the inactive position of the actuating member, depression of the actuating member into said predetermined depressed position causing pressure engagement of said portion with the spiral coil 40

thereby snapping said other spring arm into said other switching position.

3. The switching device according to claim 2 wherein the center axis of said spiral coil and a flat side wall of the actuating member portion engageable with the spiral coil are substantially disposed in a common plane normal to the plane of the circuit board whereby an initial depression of the actuating member causes sliding of the curved taper surface and the outer coil surface relative to each other and continued depression of the actuating member causes a large and abrupt deflection of said other spring arm in response to a small depression movement of the actuating member. 10

4. The device according to claim 1 wherein a pushbutton is secured to the other end of the actuating member and a mounting post extends from the pushbutton into a hole of the board slideable therein, and wherein a spring is interposed between the board and the pushbutton biasing the later into a position in which the actuating member is in said inactive position. 15

5. The device according to claim 1 wherein the arms of said V-shaped contact spring are joined at the apex thereof by a second spiral coil, and wherein said support has at its upper end a recess, said second coil being received in said recess. 20

6. The switching device according to claim 1 wherein said one arm of the contact spring is secured to a wire connected to said one conductor and including a V-shaped portion, said one end of the other spring arm engaging both branches of said V-shaped portion in said other switching position of the other spring arm. 25
